HOUSING FOR A PORTABLE HAIR DRYER

Alfred W. Madl, Mequon, Wis., assignor to John Oster
Manufacturing Co., Milwaukee, Wis., a corporation of Wisconsin

Filed Mar. 26, 1962, Ser. No. 69,412

Term of patent 14 years

(Cl. D86—10)

FIG. 3.

FIG. 4.

FIG. 1 is a perspective view of a housing for a portable hair dryer, showing my design;

FIG. 2 is an elevational view thereof;

FIG. 3 is an enlarged sectional view taken along the sectional line 3—3 of FIG. 1; and

FIG. 4 is an enlarged sectional view taken along the sectional line 4—4 of FIG. 1.

The dominant features of my design reside in the portions shown in full lines.

I claim:

The ornamental design for a housing for a portable hair dryer, as shown and described.
